UNITED STATES PATENT OFFICE.

HENRY C. LYONS, OF DUNDEE, MINNESOTA.

COMBINATION BENCH, IRONING-BOARD, AND DRYING-RACK.

1,366,127.

Specification of Letters Patent. Patented Jan. 18, 1921.

Application filed June 5, 1920. Serial No. 386,755.

To all whom it may concern:

Be it known that I, HENRY C. LYONS, a citizen of the United States, residing at Dundee, in the county of Nobles and State of Minnesota, have invented certain new and useful Improvements in Combination Benches, Ironing-Boards, and Drying-Racks, of which the following is a specification.

10 This invention relates to home laundry equipment and the object is to provide a compact combination bench, ironing board and drying rack. The invention is illustrated in the accompanying drawings, in which:

Figure 1 is a side elevation of the bench in knocked down position.

Fig. 2 is a side view similar to Fig. 1 but showing the inner construction in raised position.

Fig. 3 is an end view of the bench as seen in Fig. 2 but showing the ironing board and drying rack in extended position, a portion of the latter being broken away.

25 Fig. 4 is a fractional end view of the device showing a modified position of the drying rack.

Referring to the drawings by reference numerals, 5 designates a four walled cabinet on which rests a top 6 which when in lowered position as in Fig. 1 is adapted to support tubs or other laundry equipment. When the clothes have been cleaned and are ready to be dried and ironed the top 6 together with the end sections 7 are lifted up until the spring catches 8 snap over the top ends of the box 5 as in Figs. 2 and 3. Said sections 7 are vertically slidable in the box and are adapted to be detachably secured at their upper ends to the top 6 by spring catches 9.

An ironing board 10 is pivotally secured to the underside of the top 6 by a bolt 11, so that it may be swung in and out of the

way, as in Fig. 2, or swung out to one side 45 when it is to be used, as in Fig. 3. The board is provided with a brace 12 which has a notch 12^a at its lower end so as to engage against the top edge of one of the sides of the box 5. A hinge 13 connects the brace 50 12 to the board 10, and is provided with a spring 14 which normally holds the brace up against the board to make the construction compact and keep the brace out of the way.

The drying rack feature of this invention consists of a double set of lazytong levers 15, between the opposite corresponding joints of which are secured a series of parallel drying rods 16. The rack is pivotally 60 secured to the slidable end sections 7 and is of such construction that when in closed position will rest compactly between the sections and may be lowered together with them into the cabinet 5. When the rack 65 is to be used simultaneously with the ironing board it may be extended out to one side as shown in Fig. 3. But if it is to be used alone it may be extended directly upward as in Fig. 4, after first having released the catches 9 and removed the top 6.

Having now therefore fully shown and described my invention what I claim to be new and desire to protect by Letters Patent is:

A device of the class described consisting of a suitable cabinet, a horizontal top adapted to be raised and lowered relatively thereto, means for releasably retaining said top in raised position, an ironing board pivotally 80 bolted to the underside of said top, a brace hingedly secured at one end to the underside of said ironing board, said brace having a notch at its other end adapted to engage against one edge of said cabinet.

In testimony whereof I affix my signature.

HENRY C. LYONS.
